F. KRACZKOSKI.

WINDOW SHADE AND CURTAIN FIXTURE.

APPLICATION FILED APR. 28, 1914.

1,128,611.

Patented Feb. 16, 1915.

UNITED STATES PATENT OFFICE.

FRANK KRACZKOSKI, OF DENVER, COLORADO.

WINDOW SHADE AND CURTAIN FIXTURE.

1,128,611.

Specification of Letters Patent. Patented Feb. 16, 1915.

Application filed April 23, 1914. Serial No. 833,922.

To all whom it may concern:

Be it known that I, FRANK KRACZKOSKI, citizen of the United States, residing in the city and county of Denver and State of Colorado, have invented certain new and useful Improvements in Window Shade and Curtain Fixtures; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in fixtures for supporting spring rollers for shades and poles for the curtains of windows. My object is to provide a construction which is capable of being applied without the use of screws, nails or other fastening devices distinct from the article itself. In other words, my improvement is equipped with devices capable of adjustment, whereby the fixture may be attached or detached at pleasure without the use of tools, instruments or distinct fastening devices of any kind.

The device consists of a plate adapted to be applied to each of the upper corners of the window frame where the shade and curtains are to be located. This plate is provided with hooks which are adapted to engage the frame on opposite sides of the exterior corner of the frame, while an adjustable device is adapted to engage the interior diagonal corner of the frame. This last named device is operable by means of a small lever which engages a ratchet plate whereby when the fastening device is properly adjusted, it may be securely locked in such position.

Furthermore, the fixture is equipped to hold the curtain pole, and the spring roller, the clip which engages the adjacent extremity of the roller being adjustable to accommodate rollers of varying length.

Having briefly outlined my improved construction, I will proceed to describe the same in detail, reference being made to the accompanying drawing, in which is illustrated an embodiment thereof.

In this drawing,—Figure 1 is a fragmentary view of one of the upper corners of a

window frame, showing my improvement applied. Fig. 2 is a section taken on the line 2—2, Fig. 1, looking toward the left. Fig. 3 is a top plan view of the construction shown in Fig. 1, or a view looking in the direction of arrow 3, Fig. 1.

The same reference characters indicate the same parts in all the views.

Let the numeral 5 designate the plate forming the body of my improved device. This plate may be stamped from sheet metal so that a horizontally disposed flange 6 may engage the window frame at the top, while a similar flange may engage the vertical portion of the frame adjacent the upper corner to which the device is applied. The upper portion of the plate near the corner is equipped with an outwardly projecting pin 7, for supporting one extremity of the curtain pole 8, the latter being perforated to receive the outer extremity 9 of the pin which is threaded to receive a knob 10 which holds the curtain pole in place. The inner extremity of the pin 7 is reduced and threaded as shown at 12, to pass through an opening in part 13 of the plate which is struck up or pressed outwardly to make room for a securing nut 14 which is applied to the threaded end of the pin. Below the part 13 of the plate, the latter is depressed as shown at 15, to form a dove-tailed groove 16 adapted to receive a member 17, which is freely slideable in the groove and held in any desired position of adjustment by a set-screw 18. The slideable member 17 is provided with an outward projection 19 adapted to receive one extremity 20 of the shade roller 21.

The plate 5 is provided on opposite sides of its exterior corner 22 with hooks 23 preferably composed of wire, whose inner extremities are pivotally connected with the plate as shown at 24, their inner extremities however, passing through the plate being upset as shown at 25, whereby the hooks are held securely in place against removal. At the same time, they are capable of movement on the axes of their pivots within a considerable range, to compensate for irregularities or peculiar shapes of window frames which may be encountered in applying these devices to frames already constructed. From the pivotal extremities of the hooks, they extend outwardly and upwardly, and are bent as shown at 26, at right angles, from which point they extend rearwardly.

as shown at 27, in engagement with the flanges 6 of the plate, beyond which they are bent downwardly, as shown at 28, their extremities being pointed as shown at 29, whereby they are adapted to pierce the wood of the frame for securing purposes.

Mounted approximately in a diagonal line drawn from the corner 22 of the plate to the interior corner 30 of the window frame 10 when the device is applied, is a rod 31 which is slidable in guides 32 which, as illustrated in the drawing, may be ordinary staples, whose inner extremities are upset or riveted to hold them securely in place. The 15 lower extremity of this rod is bent rearwardly as shown at 33, and is inclined downwardly as shown at 34 beyond which it is bent upwardly, as shown at 35, and terminates in a point 36, which is upwardly directed to engage the window adjacent the stop or other part 37 of the frame. The upper extremity of this rod is bent outwardly as shown at 38, and engages a slot 39 formed in a small lever 40 fulcrumed on 20 the plate 5, as shown at 41, intermediate its extremities. Beyond the fulcrum, in a direction opposite the slot 39, the lever arm 42 which is made of sufficient length to facilitate ease of manipulation, is adapted to 25 engage a segmented ratchet 43, which may be struck up out of the plate 5. This lever is fulcrumed on the plate sufficiently loose to permit of its being raised to release it from the teeth of the ratchet when it is desired to release the rod.

In applying my improvement to the window frame, the rod 31 will be moved to the released position or that indicated by dotted lines in Fig. 1, the lever 40 in this event being 40 also in the dotted line position. The hooks 23 will be first put in place on opposite sides of the upper exterior corner of the frame. Then, by moving the lever 40 from the dotted line position in Fig. 1, to approximately 45 the position shown in full lines in the same figure, the pointed extremities 29 of the hooks 23 and also the pointed extremity 36 of the rod 31, will be caused to pierce or indent the frame in such a manner as to 50 hold the fixture securely in place.

It will, of course, be understood that each window frame must be equipped with two of these devices, one being applied to each of the upper corners of the frame.

From the foregoing description, the use 55 and operation of my improvement will be readily understood, and need not be explained further in detail.

Having thus described my invention, what 60 I claim is,—

1. A window shade and curtain fixture comprising a bracket equipped to support either end of a shade roller and curtain pole, said bracket provided with flanges for engaging the corner of the window frame on

opposite sides of the exterior angle, hooks applied to the bracket and extending beyond the edges of the said flanges to indent the frame when force is applied in the proper direction, and means for engaging the frame at the adjacent interior angle and co-operating with the said hooks for the purpose set forth. 70

2. A window shade and curtain fixture comprising a bracket equipped to support either end of a shade roller and curtain pole, said bracket provided with flanges for engaging the corner of the window frame on opposite sides of the exterior angle, hooks pivotally mounted on the bracket and extending beyond the edges of the said flanges to indent the frame when force is applied in the proper direction, and means for engaging the frame at the adjacent interior angle and co-operating with the said hooks for the purpose set forth. 75

3. A fixture of the class described, comprising a plate equipped with means for supporting a curtain pole and a shade roller at one extremity, the said device being adapted to be applied to the corner of a window frame and having flanges engaging the frame and extending in both directions from the exterior angle thereof, hooks applied to the plate and extending beyond the edges of said flanges on opposite sides of the said angle, the said hooks having sharpened extremities extending downwardly to indent the frame when force is applied in the proper direction, and a rod extending approximately parallel with the plane of the said hooks and having a hooked-shaped extremity adapted to engage the window frame at the interior angle diagonally located with reference to the exterior angle, the said rod being longitudinally movable on the plate, and means for actuating the rod to cause its hook and the first named hooks to indent the frame for securing purposes, substantially as described. 90

4. A fixture of the class described, comprising a plate adapted to be applied to the corner of a window frame and located between the exterior and the interior angles thereof, the said plate being equipped for supporting one extremity of a shade roller, and having hooks pivotally mounted on the plate and extending beyond the adjacent edges thereof and having downwardly turned sharpened extremities adapted to indent the frame on opposite sides of the exterior angle thereof, and a rod movably mounted on the plate and arranged approximately parallel with the said hooks, but intermediately located, one extremity of the rod terminating in a hook adapted to engage the interior angle of the frame diagonally located from the said exterior angle, the rod being movably mounted to cause its hooked-shaped extremity, together with the sharp- 95

ened extremity of the first named hooks, to indent the frame in securing relation, substantially as described.

5. A fixture of the class described, comprising a plate whose edges are flanged to engage the edges of a window frame on opposite sides of one of the corners, and extending beyond the exterior angle in both directions, hooks movably connected with 10 the plate and extending outwardly beyond the edges thereof, their extremities being sharpened and turned downwardly to indent the frame beyond the flanges of the plate, and a rod slidably mounted on the 15 frame and having its lower extremity bent upwardly and sharpened to indent the frame at its interior angle and diagonally located from the aforesaid exterior angle, and means connected with the said rod for 20 actuating the latter to cause its pointed extremity and the corresponding extremities of the hooks to indent the frame for securing purposes, substantially as described.
6. A fixture of the class described, comprising a plate adapted to engage a window frame adjacent the corner thereof and provided with means adapted to indent the frame on opposite sides of the exterior angle, a rod movable in guides attached to the 25 frame and located approximately in alignment diagonally with the exterior and adj-

acent interior angles, the said rod having a hook shaped lower extremity pointed to indent the frame, its opposite extremity being bent outwardly, and a lever fulcrumed on 35 the frame and having an elongated opening which the last named extremity of the rod enters, and a ratchet applied to the plate and whose teeth are adapted to engage the lever for securing the rod in the desired 40 position of adjustment, substantially as described.

7. A fixture of the class described, comprising a bracket adapted to fit the corner of a window frame and engaging the latter 45 on opposite sides of the exterior angle, securing devices applied to the fixture and adapted to indent the frame on opposite sides of the said angle, and a hook-shaped rod slidably mounted on the fixture, and 50 means connected with one extremity of said rod for adjusting the latter, whereby its hooked-shaped extremity is caused to indent the frame at its interior angle, for the purpose set forth.

In testimony whereof I affix my signature in presence of two witnesses.

FRANK KRACZKOSKI.
